NOZZLE STOPPER

Ralph L. Swank, Johnstown, Pa.

Application July 18, 1941, Serial No. 402,899

2 Claims. (Cl. 22—85)

This invention relates to the construction and manufacture of nozzle stoppers, or stopper rods as they are sometimes referred to in the steel foundry industry, for controlling the pouring of molten metal from ladles into ingot molds or flasks designed to give the shapes of castings wanted.

The ladle for holding the liquid must of necessity not leak and provision must be made for the removal of the liquid through a hole left in the bottom of the ladle. The flow of this liquid must be controlled in order that the ladle may be moved from one mold to another without spillage, until the ladle is emptied of its contents. To accomplish this the stopper rod is used and on the end of this rod is placed a head usually of carbon or clay designed to adjust itself properly on the seat of the nozzle. The stopper rod is operated by a man from the pouring platform by means of a lever which gives the stopper rod a raising and lowering movement. When raised the nozzle opens to allow the metal to flow and when lowered the flow of metal through the nozzle is shut off.

The stopper rod being of steel would melt and be useless unless protectively covered by a refractory material. Heretofore the protection has been provided by sections of refractory material of various sizes which are commonly known within the refractory, steel and foundry industries, as sleeves or stopper rod sleeves. Such sleeves are commonly provided with a male and female joint as component parts of the body of the sleeves and with attendant exacting dimensional limitations to permit of their properly fitting together. Whenever the joints as described do not fit properly, the operators seldom try to use the sleeves due to the risk involved of molten steel infiltrating through the joint and attacking the steel rod itself and burning it off, causing loss of control of the flow of the remaining metal in the ladle through the nozzle with resultant monetary loss and in instances the severe burning of workmen with fatal results. No consumer of sleeves would knowingly use sleeves with the male and female joint not properly fitting and thereby endanger property and human life. With this type of joint severe accidents can happen and have happened. Only one defective sleeve joint on a stopper rod, which may not have been noticed during assembly, is enough for complete spoiling of the ladle contents. Furthermore, the use of the male and female type of joint on a sleeve, permits of no flexibility in the use of that sleeve along with other such sleeves of dif-

ferent dimensions. Sleeves as heretofore produced, with the male and female joint, are made with various outside diameters, such as 4", 4½", 4¾", 5", 5¼", 5½", 5¾", 6" and larger, also some in-between sizes, each carrying a male and female joint of different dimensions and proportions. This practice has precluded the use of one size of sleeve with another size sleeve on the same stopper rod assembly. Furthermore, the male and female joint types of sleeves are quite susceptible to breakage or damage before assembly, the male end equally so with the female end, entailing the possibility of applying defective sleeves to the stopper rod without the defect being noticed and so enhancing the possibility of accidents.

Typical stopper rod assemblies of well known types are shown in patents to Hiram Swank, No. 161,644 and Andrew J. Haws No. 205,084, the latter showing the commonly employed male and female type of joint.

By virtue of the invention herein described, the male and female type of joint with its inherent disadvantages is eliminated. Instead the sleeve is made with an indenture at each end which is not necessarily of one particular size or shape but is centrally located to enlarge the hole at the sleeve end. A number of cross sectional shapes of the hole in the sleeve can be adopted with attendant advantages but without affecting the utility of the stopper rod assembly or detracting from the efficiency of the joint. In assembling sleeves, indented in this way, on the stopper rod, the cavity provided between adjacent sleeves by the juxtaposed indentures, is filled with plastic refractory material. Precise or even approximate registry of the indentures is not necessary. This material when dried forms an effective seal at the joint and serves to support the sleeves concentrically at their ends upon the steel rod.

The sleeves used in this new stopper rod assembly are preferably formed by the extruding method which is most economical and by subsequent grinding of the indentures at the sleeve ends. On the other hand there is no known way to produce the old male and female type of joint other than by pressing the sleeves in a mold. Any attempt to grind the male end would result in the grinding tool tearing or shattering the protruding dried clay part of the sleeve at that end.

The process of making the sleeves with indentures at both ends is as follows: A perforated column of plastic refractory material is extruded and squarely cut off into sleeve lengths or sec-

tions while in the plastic stage. The individual sleeves are then dried and the centrally positioned indentures are formed by suitable grinding tools. Both ends of a sleeve may be thus formed in one operation. When so formed the sleeves are baked in a kiln.

The hole through the sleeve is preferably non-circular in cross section. It may, for example, be fluted, thus insuring ample air pocket space between the rod proper and the surrounding sleeve. The fluting of the interior surface of the sleeve adds strength with a saving in weight of the material. The fluted hole can readily be formed in the extruding step. Because of the safety features contributed by the joint, sleeves made in this way, i. e., by the extruded and grinding method may be formed in greater lengths than is practical with the old male and female type of sleeve.

A description of a stopper rod assembly embodying the invention follows, with reference to the accompanying drawing wherein,

Fig. 1 illustrates a portion of a nozzle stopper assembly, partly in longitudinal section.

Fig. 2 is a cross sectional view on the line 2—2 of Fig. 1.

Figs. 3 and 4 are views similar to Fig. 2 showing practical variations in the cross sectional shape of the hole in the sleeve, and

Figs. 5 to 9 are fragmentary views in longitudinal section showing several practical variations of shape of the indentures at the ends of the sleeve.

A steel rod 11 for raising and lowering a head 12 secured to the lower end of the rod by a bolt 13 is protected throughout that part of its length which is to be immersed in the molten steel by a series of sleeve sections such as 14, 15 and 16 which abut one another end to end. Each sleeve preferably has a hole fluted in cross section, as shown in Fig. 2, or the hole may be round in cross section as shown in Fig. 3, or be of polygon shape as shown in Fig. 4. The advantages of the non-circular hole in the sleeve are that air pockets 10 still will be maintained at any side of the rod should it bend that way. At the same time with a given amount of air space, the rod is better held against excessive bending than by a sleeve having a round hole.

The indentures at the end of the sleeve sections may be of bevel shape as shown at 17 in Fig. 1, simple concave, as shown at 18 in Fig. 5, convex, as shown at 19 in Fig. 6, bevel with a notch 20 in the beveled surface and a notch 21 in the end surface, as shown in Fig. 7, concave with a notch 22 in the concave surface, as shown in Fig. 8, or convex with a notch 23 in the convex surface, as shown in Fig. 9. These several shapes at the sleeve ends are of a like character in that they all provide centrally positioned indentures that, when in juxtaposed positions, form cavities. These are filled with plastic refractory material such as clay 24 to obstruct the entrance between

the sections of heat from the molten metal to the rod 11. When the clay is dried out it forms, together with the sleeves, a complete and effective protective covering throughout the length of the rod and holds the steel rod apart from the inner surfaces of the sleeves, leaving annular air spaces 9 for further protection between the rod and sleeves.

The sleeve sections are preferably manufactured by extruding a perforated column of plastic clay, squarely cutting off the column into sleeve sections of the desired lengths, drying the sections and then grinding indentures at both ends thereof. After being thus formed the sections are baked to prepare them for use as hard refractory sleeves. Usually with the steel rod held horizontally, the head is first fastened thereto at one end. The workman then wipes plastic clay over the end of the head and shoves a sleeve over the other end of the rod, pushing it on until it meets with the head. He then applies enough plastic clay to the following end of that first sleeve to fill a cavity provided by two juxtaposed indentures and shoves on another sleeve until it meets with the first one. This causes the plastic clay 24 to be molded into the cavity, which is thus filled completely. A little of the clay may squeeze in between the abutting end surfaces of the sleeves, as at 25, and more will flow into contact with the steel rod adjacent the joint. When the rod is thus fully covered by sleeves and plastic clay in this manner, a nut on the threaded upper end of the rod is drawn down to push the sleeves together and hold them in place. Then the rod is placed in a drying oven after which it is ready to be hung in the ladle to receive the molten metal when the nut may be released somewhat to permit of thermal expansion.

I claim:

1. In a nozzle stopper for ladles, the combination with a rod, of a series of perforated sections of baked refractory material covering said rod, each of said sections having indentures centrally positioned at each end thereof, and plastic refractory material filling the cavities between adjacent sections provided by such indentures.

2. In a nozzle stopper for ladles, the combination with a rod, of a series of perforated sections of baked refractory material concentrically embracing said rod and substantially covering it lengthwise, the cross-sectional area of the perforations of said sections being greater than the cross-sectional area of said rod, each of said sections having indentures centrally positioned at each end thereof, and plastic refractory material filling the cavities between adjacent sections provided by such indentures and contacting said rod to support said sections thereupon and maintain annular air spaces between said sections and said rod.

RALPH L. SWANK.
